(57) **CLAIM**

The ornamental design for a high wall tray extension, as shown and described.

DESCRIPTION

FIG. 1 is a perspective view of a high wall tray extension attached to a tray.

FIG. 2 is a perspective view of the high wall tray extension detached from the tray.

FIG. 3 is a perspective view of a back piece of the high wall tray extension;

FIG. 4 is a front view thereof;

FIG. 5 is a back view thereof;

FIG. 6 is a right-side view thereof;

FIG. 7 is a left side view thereof;

FIG. 8 is a top view thereof;

FIG. 9 is a bottom view thereof;

FIG. 10 is a perspective view of a side piece of the high wall tray extension;

FIG. 11 is a front view thereof;

FIG. 12 is a back view thereof;

FIG. 13 is a right-side view thereof;

FIG. 14 is a left side view thereof;

FIG. 15 is a top view thereof; and,

FIG. 16 is a bottom view thereof.

The broken lines are for illustrative purposes only and form no part of the claimed design.

1 Claim, 8 Drawing Sheets
